J. H. WILLIAMS

INHALATION DEVICE

Filed April 10, 1923

Fig. 4.

Fig. 5.

Inventor:
Josiah H. Williams,

Attorney.

UNITED STATES PATENT OFFICE.

JOSIAH H. WILLIAMS, OF BALTIMORE, MARYLAND.

INHALATION DEVICE.

Application filed April 10, 1923. Serial No. 631,218.

This invention relates to a device for use in the treatment of affections or diseases of the respiratory organs by inhalation of medicinal substances, and the present invention is designed to provide certain improvements upon the type of inhalation device shown in my prior Patent No. 1,387,030, dated August 9, 1921, which device is adapted to be supported upon the chest of a recumbent or sleeping patient whereby the healing vapors emanating from a volatile medicament may be directed toward the mouth and nostrils of a patient, so that at all times during the respiration of the patient the air inspired will be impregnated with the healing agent.

One object of the present invention is to provide an inhalation device embodying a vapor collecting and delivering receptacle which may be employed for collecting and delivering for use medicated vapor generated by the heat of the body from medicament applied to the patient's chest, or vapor suitably liberated or generated within the receptacle itself, or vapor generated by a suitable external vaporizing device from which the vapor is conducted to the receptacle.

Another object of the invention is to provide a receptacle preferably made of a single piece of waterproof or washable material and adapted to be folded and its portions secured to form the receptacle, and which after each use or whenever desired, may be unfolded into substantially flat shape and readily washed or otherwise cleansed so that the device may be kept in a thoroughly sanitary condition.

Still another object of the invention is to provide improved means for holding the walls of the receptacle distended and in proper shape for use and for supporting within the receptacle a cup or the like to contain medicament to be vaporized, and further to provide means whereby any moisture contained in the vapor supplied from a vaporizer may be separated from the vapor and collected for discharge.

Still another object of the invention is to provide a device of the character described which is simple, inexpensive and efficient in construction, and which may be compactly packed for sale and storage in transportation or when not in use.

With these and other objects in view, the invention consists of the features of construction, combination and arrangement of parts, hereinafter fully described and claimed, reference being had to the accompanying drawing, in which:—

Figure 1 is a perspective view of the device as formed ready for use.

Figure 2 is a central vertical front-to-rear section through the device shown in Figure 1.

Figure 3 is a perspective view of the expandable and collapsible frame and a medicament cup held thereby.

Figure 4 is a top plan view of the receptacle in unfolded and outspread condition.

Figure 5 is a section on the line 5—5 of Figure 2.

In carrying my invention into practice, I provide an inhalation device comprising a receptacle 1 of somewhat greater length than width and of suitable form and size to rest upon the chest of a recumbent patient. This receptacle, which may be made of any suitable material or combination of materials, but preferably of rubber, rubberized fabric or other suitable impermeable and washable material, includes a bottom wall or layer 2, a top wall or layer composed of a central portion 3 and end portions 4, and front walls 5. The wall or layer 2, by reason of the flexibility of the material of which the receptacle is made, is adapted to lie in close contact with the chest and conform to the contour thereof, while the wall portions 2, 3, 4 and 5 are also adapted, by reason of the flexibility of the material, to assume the form shown in Figures 1 and 2 when the receptacle is distended and are capable of folding, as hereinafter described, so as to permit the receptacle to collapse in substantially flat form when not held distended, so that it may be conveniently stored when not in use and packed in compact shape in a box or like container for sale or transmission through the mails.

In practice, the receptacle may be made of two or more pieces of material, but, for sake of simplicity and economy of construction, it is preferably made of a single piece of material cut to the shape shown in Figure 4. The blank or sheet shown in Figure 4 from which the receptacle is formed, is preferably provided with a reinforcing and finishing

edge binder 6 of tape or other suitable material. In producing the receptacle from this blank or sheet, the blank or sheet is folded along the dotted line *a—a* to produce superposed top and bottom wall sections and is then folded along the dotted line *b—b* to produce the downturned front wall portions 5. The end of the blank, which forms the front portion of the top wall of the receptacle, is suitably shaped beyond the fold line *b—b* to provide the triangular flaps which form the front walls 5 and also to provide an intermediate flap 7 for a purpose hereinafter described.

15 The bottom wall 2 is provided with perforations 8 over a large portion of its area to render it sufficiently porous to permit the animal heat to pass from the chest of the patient into the receptacle, and which will also permit vapors generated by such heat to pass into the receptacle, in cases where the medicament is supplied directly to the chest of the patient. The wall portions 3, 4 and 5, on the contrary, are imperforate in order to prevent direct upward escape of the heat and vapors and to confine the same within the receptacle for discharge at the front thereof through a vapor discharge outlet 9 formed between the forward edges 30 of the bottom and top walls and the spaced walls 5. It will be observed that, as the bottom and top walls of the receptacle 1 are directly joined at their outer longitudinal edges and connected at their front edges—

35 on opposite sides of the outlet 9—by the triangular walls 5, the top wall as a whole slopes or inclines in a forward and upward direction, the receptacle chamber thus being of minimum depth at the rear and of maximum depth at the front. Also as the outer edges of the top wall sections 4 are directly secured at their outer edges to the corresponding edges of the bottom wall, the receptacle chamber is of minimum depth at its 40 lateral edges or sides and of maximum depth at the center in the direction transversely of said receptacle. As a result, the central portion 3 of the top wall slopes continuously in an upward and forward direction between its rear and front edges, while the side portions 4 of said top wall slope similarly to the top wall between their rear and front edges but also slope outwardly and downwardly from the central portion 3 of the top wall toward the outer edges of the bottom wall 2 to which they are joined. By this construction the portions 3 and 4 act as deflectors to not only guide the entering vapors toward the center of the receptacle, but also to guide said vapors toward the central front outlet 9. Thus while a receptacle of ample size to receive an adequate quantity of vapor at all times is produced, all the vapor may be discharged through a comparatively small outlet and thereby concen-

trated and emitted in such close proximity to the mouth and nostrils of the patient that the surrounding atmospheric air inspired by the patient will be densely impregnated with the vapors.

Fastening devices are provided for connecting the proper meeting edges of the wall portions to hold the walls in receptacle forming relation. These fastenings may be of any approved construction, but are preferably of the separable fastener type. As shown, spring studs 10 are provided at the lateral edges of the wall 2 for engagement with spring sockets 11 upon the lateral edges of the wall portions 4, and similar studs 12 and sockets 13 are provided upon the front edge of the wall 2 and at the inner lower corners of the walls 5 for interengagement to secure said walls 5 in closed condition. With this construction, it will be apparent that the walls of the receptacle may be held connected in a secure manner, but that upon disengaging the sockets 11 and 13 from the studs 10 and 12, the walls 3, 4 and 5 will be released at their free marginal edges from the wall 2, allowing the top section of the receptacle to be thrown back and the material of the receptacle to be outspread in the blank or flat form shown in Figure 4, in which form all portions of the receptacle may be reached so that the receptacle may be thoroughly washed or cleansed whenever required or desired and thereby maintained in a sanitary condition.

The receptacle is designed to be held when in use in a distended position by means of an expansible and collapsible or foldable frame 14. This frame is of a length equal to the width of the receptacle, but is of restricted width relative to the length of the receptacle, being of a width substantially equal to that of the outlet 9 and of the central portion 3 of the top wall. This frame is substantially V-shaped and comprises top and bottom walls or members 15 and 16 connected by spring hinges 17 at the rear or vertex portion of the frame, said hinges serving to hold the frame members open or spread as shown in Figure 3, and adapting them to be closed or folded in substantially parallel relation. The frame is fitted in the central portion of the receptacle 1 with the vertex portion thereof facing in the direction of the line of fold between the wall portions 2 and 3, and with the members 15 and 16 lying in contact with said wall portions, as shown in Figure 2. Hence when the members 15 and 16 are free for spreading motion, the wall portions 3 and 4 (the portion 3 directly and the portion 4 indirectly) will be elevated, thus holding the receptacle 1 distended.

Preferably the members 15 and 16 and the hinges 17 of the V-shaped frame are made from a single piece of spring wire, the

central portion of which is bent to form the cross-bar 18 and side arms 19 of the lower U-shaped frame member 15, thence bent to form the coiled spring hinges 17, and finally bent to form the side arms 20 and cross-bar 21 of the U-shaped frame member 16, the ends of the wire terminating in the bar 21 and being united, as by means of a coupling 22. The frame structure may be completed by providing the frame members with suitable braces, as by providing member 15 with a cross brace 23 between its arms 19, and by providing member 16 with a cross brace 24 and diagonal braces 25 between its side arms 20. The lower frame member 15 is shorter than the upper frame member 16 and is designed to have its cross-bar portion 18 terminate some distance inwardly of the outlet 9 of the receptacle, while cross-bar 21 of the member 16 projects a greater distance forwardly and through and beyond the outlet 9. The bar 21 is thus positioned to permit the free edge of the central flap 7 of the upper receptacle wall to be extended outwardly over and then under said bar 21, as shown in Figures 1 and 2, thereby forming a visor-like projection at the top of the opening 9 and extending beyond the walls 5, which projection will serve as a deflector to guide the discharging vapors beyond the outlet and sufficiently close to the mouth and nostrils of the patient to ensure their inspiration with the air. Spring studs 27 are provided upon the free edge of flap 7 to engage sockets 28 upon the body of said flap whereby such portions of the flap may be united in rear of the bar 21 to produce the projection described and to connect the top wall of the receptacle positively to the upper frame member of the spring frame. This connection incidentally serves as a means for holding the spring frame within the receptacle against displacement, but any additional fastening connections for this purpose, for holding the spring frame either permanently or detachably fastened in position, may be employed.

As stated, the device may be used for collecting and distributing to the air inspired by the patient vapors produced by the animal heat from the patient's body, when the medicament used, such as a salve, consisting of a petroleum base containing the volatile crystals of essential oils or healing agents, is applied directly to the patient's chest, in which event such vapors will enter the receptacle through the openings 8 and discharge therefrom through the outlet 9. The medicament used may, however, be a vaporizable liquid contained within the receptacle and volatilized by the heat from the patient's body. In this instance the liquid medicament may be contained within a cup 29 of suitable kind to receive a sponge or body of absorbent material 30 saturated with the

liquid therefrom, and whereby the liquid is held in condition to be readily vaporized. This cup may be supported by the spring frame 14, and, as shown for that purpose, the cross-bar 18 of the lower frame member 15 is offset inwardly to provide a partially circular spring clip 31 to engage an annular groove or recess 32 in the body of the cup, whereby under the spring pressure of arms 19 exerted on the sides of the clip the cup is firmly held in position for use but may be readily disengaged when desired. It will also be observed that the forward portions of arms 19 adjacent to the clip 31 are offset upwardly into a horizontal plane above the plane of the rear portions of said arms, thus elevating the clip carrying portion of the frame so that it will hold the cup elevated above the bottom of the receptacle and provide space for its occupancy and more convenient insertion and removal. I further provide means whereby vapor supplied from a vapor generator of suitable character separate from the receptacle may be used, for which purpose the receptacle is provided centrally of the line of fold between its top and bottom walls with a shouldered nipple 33 to receive one end of a rubber or other tube 34 through which vapor may be conducted from the generator to the receptacle. If the generator is of a type which supplies steam with the oil vapor, or which supplies vapor containing a certain amount of moisture, a catch basin 35 may be provided at a suitable point in the length of the tube 34 to catch and retain the water of condensation or moisture and prevent the same passing to the receptacle. The catch basin 35 shown in the present instance is arranged between two sections of the tube or pipe 34 and provided with diametrically extended shouldered-nipples 36 for connection with the proximate ends of said pipe sections, whereby it is properly arranged in the line of flow of the vapor and is adapted to be detached from the pipe sections for discharge of the moisture and cleaning whenever occasion requires. The receptacle is thus adapted for use for supplying vapor under different conditions and from different sources, as may be desired or required, and may use as its source of supply of medicated vapor any of the vapor generators in general use.

The receptacle may be held in position for use against casual displacement in any preferred manner. In the present instance I have shown straps 37 and 38 for securing the receptacle to the body of the patient or to portions of a bed frame or the bedding thereof or to portions of a couch on which the patient may lie to receive treatment. The strap 37 may, for example, be looped around the shoulders and the strap 38 around the chest of the patient to hold the device in position.

sition, or they may be secured to portions of a bed or couch frame or to bed clothing or upholstery, as may be desired or found most suitable under the circumstances. As shown, 5 strap 37 is provided at one end with an eyelet 39 by means of which it may be placed between the wall portions 2 and 5 at one side of the outlet 9 and secured by one set of fastenings 12 and 13, while the opposite end of 10 the strap is provided with a plurality of eyelets 40 for adjustable engagement with the similar fastenings 12 and 13 connecting the walls 2 and 5 at the opposite side of the outlet 9. The strap 38 has its intermediate portion 15 extending transversely of the receptacle between the top and bottom walls thereof and provided with spaced eyelets 41 for engagement with the studs of aligned sets of fastenings 10 and 11, and the ends of said strap 20 38 extend beyond the sides of the receptacle so that they may be tied together or they may be provided with any suitable type of fastening means for fastening connection with each other. It will be observed that 25 the separable fastenings connecting the receptacle walls also detachably secure the straps 37 and 38 in place, ensuring simplicity of construction, and admitting of the disconnection of said straps from the receptacle in 30 a convenient manner whenever the device is opened for a cleansing action.

It will be understood that the weight of the frame 14 will hold the central part of the bottom wall 2 of the receptacle in close 35 contact with the center of the chest of the patient, allowing the ends of said wall to assume the curvature of the sides of the chest and lie in close contact therewith. This is of 40 importance in collecting the body heat of the patient and transmitting the same to the inferior of the receptacle when vapors are to be generated in said receptacle and such vapors kept in a vaporized state. Close contact of 45 the layer 2 with the chest is also of importance when a medicament containing the vaporizable substance or substances is applied directly to the chest or to the wall 2. When 50 the device is applied for use the spring coils 17 hold the upper frame member 16 of the frame 14 elevated, whereby the receptacle will be held distended or its upper wall elevated and in proper condition for use. The 55 device may thus be supported on the chest of the wearer sufficiently close to the mouth and nostrils to saturate the inspired air with the vapor, but not so close as to prevent the patient from breathing in a requisite amount of air. Normal respiration will, therefore, be permitted and waste of vapors prevented, 60 while the air inspired will be impregnated with just the right proportion of healing vapor to give the proper therapeutic effect. The frame 14 may be removed whenever it is desired to allow the receptacle to be collapsed for close contact in storage or ship-

ment, or it may be allowed to remain in the receptacle and its upper frame member pressed downward to collapse the frame with the receptacle, in which condition the receptacle may be held by proper use of one 70 or both of the straps 37 or 38 or through the medium of other suitable fastening means. In either case the device may be collapsed in very close compass for storage or package in a box for transportation or sale or for package in a suitcase or other traveling receptacle, the advantages of which may be apparent. A valuable feature of the device is, as 75 described, that it may be opened out flat and all of its parts disconnected so that it may be washed or otherwise cleansed, enabling the device to be kept in a thoroughly sanitary condition at all times.

Having thus fully described my invention, I claim:—

1. An inhalation device comprising a receptacle formed of flexible sheet material, said receptacle having top and bottom walls permanently joined at their rear longitudinal edges only and detachably connected at their side edges, one of said walls being provided at its front edge with front wall sections detachably connected with the other of said walls, said front wall sections being spaced to provide a vapor outlet, and said top wall having a flap in line with said outlet, and a spreading device within the receptacle comprising resiliently connected top and bottom members, the top member having a forward portion projecting through the outlet beyond the front wall sections, said flap adapted to be folded under said forward portion of the top member and to be detachably connected at its free edge with the top wall of the receptacle, the construction being such that upon disconnecting said walls and flap at their points of detachable connection the receptacle may be outspread in the form of a substantially flat sheet.

2. An inhalation device comprising a receptacle formed of flexible material and having a front vapor outlet and top and bottom walls, and a spring frame in said receptacle for holding said walls spread, said frame having resiliently connected U-shaped top and bottom members bearing against said walls and each including side arms and a front cross bar, a portion of the front cross bar of said bottom frame member being offset inwardly so as to form an integral spring clip and the forward portions of the side arms of said frame member being offset upwardly to dispose said cross bar above the plane of the remaining portions of said side arms, and a medicament holding cup adapted to be engaged by said clip.

3. An inhalation device comprising a receptacle formed of flexible material and having top and bottom walls, said walls be-

ing connected at their rear and side edges and relatively sloping toward their front edges, front wall sections connecting the front edges of the top and bottom walls and 5 spaced from each other to provide an intervening central outlet at the front of the receptacle, a spreading device within the receptacle having a bottom member bearing on the bottom wall and a top member bearing on the top wall and spacing the same from the bottom wall, said top member having a U-shaped front portion projecting forwardly beyond the forward edge of the bottom member and through said outlet beyond the 10 vertical plane of the front wall, and a flap upon the front edge of the central portion of the top wall covering the upper surface of said projecting portion of said top member and folded under the same and forming 15 therewith a visor-like deflector extending beyond and overhanging said outlet.

4. An inhalation device comprising a receptacle formed of flexible material and having top and bottom walls, said walls being 20 directly connected at their rear and side edges and free from direct connection at their front edges, the said front wall being provided with an upwardly and forwardly sloping central portion and upwardly and 25 forwardly and downwardly and outwardly sloping side portions, triangular front walls connecting the side portions of the top wall at their front edges with the front edge of the bottom wall, said front walls being 30 spaced to provide an intervening outlet, a spreading device within the receptacle having a member bearing on the top wall and spacing the same from the bottom wall and having a portion projecting forwardly 35 through said outlet beyond the vertical plane of the front wall, and a flap upon the front edge of the central portion of the top wall folded under said projecting portion of said spreading device and forming therewith a 40 deflector extending beyond and overhanging said outlet.

5. An inhalation device comprising a receptacle made of flexible material and having top and bottom walls permanently joined 45 at their rear longitudinal edges and normally free from connection at their side and front edges, front wall forming flaps at the front edge of the top wall arranged on opposite sides of the center thereof so as to provide 50 an intervening outlet at the front of the receptacle, stud and socket members upon the side edges of the top and bottom walls detachably connecting said edges, stud and socket fasteners upon the flaps and front 55 edge of the bottom wall and detachably connecting said flaps with said bottom wall, a strap adapted to be extended through the receptacle between the top and bottom walls and provided with eyelets adapted for 60 detachable engagement with certain of the

first-named studs and sockets, and a strap having end portions adapted to be disposed between the flaps and front edge of the bottom wall and provided with eyelets for detachable connection with the studs and sockets 65 connecting said flaps and bottom wall.

6. An inhalation device comprising a receptacle formed of flexible material and having top and bottom walls united by their rear and side edges, front walls connecting 70 said top and bottom walls on opposite sides of the center thereof and forming an intervening vapor outlet, a flap projecting from the central portion of the front edge of the top wall, a spring frame within the receptacle having a lower frame member resting on the bottom wall and an upper frame member bearing against the top wall and forced against the latter-named wall by spring pressure, said upper frame 75 member being provided with a portion projecting beneath said flap and beyond the vertical plane of the front wall, said flap having its free edge folded under said projecting portion of the upper frame member and 80 detachably secured to the body portion of said flap.

7. An inhalation device comprising a receptacle formed of flexible material, said receptacle having bottom and top walls arranged to meet and permanently joined at their rear edges and spaced at their front edges, spaced front wall portions extending between the front edges of said bottom and top walls on opposite sides of the center 90 thereof and forming a central outlet, a central flap upon the front edge of said top wall, and a spring frame for holding the top and bottom walls spread at the center of the receptacle, said frame having top and bottom 95 frame portions resiliently connected at their rear edges and free for spreading motion at their front edges, the said upper frame member having its forward edge extending through and outwardly beyond the plane of 100 said central outlet, said central flap being adapted to be turned under the projecting forward edge of the upper frame portion of the spring frame and secured to form therewith a visor-like projection overhanging 105 said central opening.

8. An inhalation device comprising a receptacle formed of flexible material, said receptacle having bottom and top walls arranged to meet and permanently joined at their rear edges and spaced at their front edges, spaced front wall portions extending between the front edges of said bottom and top walls on opposite sides of the center 110 thereof and forming a central outlet, a central flap upon the front edge of the said top wall, and a spring frame for holding the top and bottom walls spread at the center of the receptacle, said frame having top and bottom frame portions resiliently connected 115

120

125

130

at their rear edges and free for spreading motion at their front edges, the said lower frame member having its front edge bent to provide a spring clip and the said upper frame member having its forward edge extending through and outwardly beyond the plane of said central outlet, said central flap

being adapted to be turned under the projecting forward edge of the upper frame portion of the spring frame and secured to form therewith a visor-like projection overhanging said central opening.

In testimony whereof I affix my signature.

JOSIAH H. WILLIAMS.
